1862. Oct.

John C. Moore New York, New York
Letter Patent (Design No 114) dated 3rd Oct 1862.

The schedule referred to in these Letters Patent and in
Ring Part of the same.

To all whom it may concern: Be it known that I John C. Moore of the City, County and State of New York have invented a mode of a new design or figure for a "die" to "strike up," or emboss the handles of Spoons, Butter Knives, Fish Knives, or tasters, whether of silver, Gold or other metal, and I do hereby declare that the following is a full and exact description of the same. Letters A & B, are the obverse and reverse sides of the spoon, representing the design or figure embossed on the handle. Figure 1, of letter A shows the head of the spoon, having three raised threads or heads, the middle one being heaviest, and forming an oval and terminating at each extreme with representations of leaves. Figure 2 represents a stem running the length of the handle and having a leaf at the commencement of the bowl of the spoon, and two threads or heads terminating at the lower end of the oval, the inner one branching into two leaves. Figure 3 of letter B represents the same design as shown in figure 1st of letter A. Figure 4 represents a depressed stem, terminating in a broad fine pointed leaf at the shank of the spoon, and having as in figure 2, two threads or heads, the inner head branching into two leaves at the head of the stem and lower part of the oval.

Having now fully described my design for embossing and ornamenting the handles of spoons, Fish or Butter Knives, or tasters, I will proceed to state what I claim therein as new and wish to secure by letters patent.

First. I claim the design of making three threads or heads as represented in the drawings terminating at the extremes of the oval.

Des. 114

2

Second. The stem as shown on the obverse and reverse sides of the spoon, in combination with the design of the threads, terminating in leaves at the lower end of the oval, and the particular shaped leaves at the shanks and commencement of the bowl of the spoon. Third. The combination of the particular configurations as represented on the obverse and reverse sides of the model and drawings.
